Application March 19, 1958, Serial No. 722,562

16 Claims. (Cl. 257—81)

This invention relates to heat exchange devices and deals more particularly with apparatus for heating or cooling flowable solids which are fed through the apparatus continuously.

A primary object of the invention is to provide a flowable solids heat exchanger wherein a high percentage of the solids passing through the exchanger is exposed to direct contact with heat transfer surfaces.

Another object of the invention is to provide a flowable solids heat exchanger wherein the conveying motion of the device is employed to continuously circulate heat exchange fluid over the heat transfer surfaces at a selectively controlled rate.

Another object of the invention is to provide a flowable solids heat exchanger wherein a plurality of heat transfer elements are continuously moved through the material and heat exchange fluid is circulated through each element during its passage through the material.

Another object of the invention is to provide a flowable solids heat exchanger wherein each heat transfer element is charged with heat exchange fluid during the initial portion of its passage through the material and is drained of heat exchange fluid between successive passages through the material.

Still another object of the invention is to provide a flowable solids heat exchanger wherein the heat exchange elements are of simple construction and are easily cleaned of deposits which may be left by the heat exchange fluid.

Other objects and advantages of the invention will become apparent by reference to the following specification taken in conjunction with the accompanying drawings.

In the drawings,

Figure 1 is a longitudinal, vertical sectional view of a heat exchanger embodying the invention;

Figure 2 is a transverse, vertical sectional view taken approximately along the line 2—2 of Fig. 1, and;

Figure 3 is another transverse, vertical sectional view taken along the line 3—3 of Fig. 1.

The heat exchanger shown in the drawings includes a horizontal drum assembly designated generally by the numeral 10 which includes a large diameter hollow cylindrical central section 12, a reduced diameter hollow cylindrical feed section 14 and a hollow cylindrical discharge section 16. The feed section 14 and the discharge section 16 are fixedly secured to the central section 12 by annular end plates 18 and 20, respectively, which may be secured to the respective sections by any suitable means such as welding.

The drum assembly 10 is supported for rotation about its longitudinal axis with the drum partially submerged in a body of heat exchange fluid 22 which is contained within a tank 24 of any suitable construction. The rotary support for the drum assembly 10 includes two concentric hardened steel tires 26 and 28 which are respectively mounted upon the feed section 14 and the discharge section 16. Each drum tire is rotatably supported by a pair of rollers, one on each side of the verti-

cal plane on which the sectional view of Fig. 1 is taken to provide a four point support for the drum. Only one such roller is shown in the drawings and appears at 30 in contact with the tire 28. To prevent undesired movement of the drum 10 in an axial direction, one of the tires, such as the tire 26, may be engaged by a pair of axially spaced rollers 32.

The drum assembly 10 is driven in rotation by coupling a suitable source of power to a driven gear or sprocket 34, which in the disclosed embodiment is mounted upon the discharge section 16.

In some instances, it is desirable to provide a cover member for the tank 24. Such a cover member is designated 36 in the drawings and is preferably constructed to include a vent assembly 38 to permit the escape of vaporized heat exchange fluid from the interior of the assembly. Where such a cover member is provided, it is generally desirable to provide drip seals between the stationary tank and cover and the rotating drum assembly 20 as at 40 and 42.

Flowable solids are fed into the interior of the drum 10 by means of a chute or tube 44 which projects into the interior of the feed section 14 through an opening 46 formed in an end wall 48. An internal conveying screw 50 is mounted in the interior of the feed section 14 to feed the material through the feed section and into the interior of the central section 12 through the open right-hand end of the feed section 14 which is in registry with an enlarged central opening 52 in the annular end plate 18.

The discharge section 16 is likewise provided with an internal conveying screw 54 for conveying material from the right-hand or discharge end of the central section 12 through the open discharge end of the discharge section 16.

Heating or cooling of the materials passing through the drum assembly 10 is accomplished during the passage of the material through the central section 12 of the drum assembly. The heat transfer elements employed to heat or cool the material within the central section 12 take the form of a plurality of longitudinally extending hollow tubes 56, the opposite ends of which respectively project through the annular end walls 18 and 20. Each of the end walls 18 and 20 is formed with a plurality of openings for receiving the ends of the tubes, the openings being located symmetrically about the axis of the drum assembly 10 and preferably lying at a common radial distance from the axis of the drum. The respective ends of the tubes are sealingly secured to their associated end walls to prevent the entry of cooling fluid from the tank 24 into the interior of the central section 12.

In the disclosed embodiment, the openings formed in the end walls 18 and 20 are in axial alignment with each other, as may best be appreciated by reference to Fig. 2 of the drawings. However, the tubes 56 do not extend between axially aligned openings but are instead extended between an opening in the plate 20 to an opening in the plate 18 which is angularly displaced about the axis of the drum assembly 10.

This may best be appreciated by identifying the ends of the tubes 56 which project through the annular end plate 20 at the discharge end of the central section 12 as inlet ends 58 and by identifying the ends of the tubes 56 which project through the annular end plate 18 as outlet ends 60. Two adjacent tubes have been identified in Fig. 2 as 56a and 56b. The circumferential location of the inlet end 58a of the tube 56a is shown as being angularly displaced by some 90° from the circumferential location of the outlet end 60a of the tube 56a. The amount of angular displacement about the axis of the drum assembly 10 of the respective inlet ends 58 and outlet ends 60 is equal both in amount and direction for all of the

tubes 56, and hence the tubes 56 may be said to be disposed symmetrically about the axis of the drum assembly 10.

As indicated by the arrow A of Fig. 2, the direction of rotation of the drum assembly 10 is clockwise when the drum is viewed from its feed end. The purpose served by the angular inclination of the tubes 56 to the axis of the drum may be best appreciated by following the movement of one of the tubes. Since twelve tubes are disclosed in Fig. 2, it will be convenient to refer to the successive locations of the inlet and outlet ends of the tubes by referring to these positions as though they were represented by numerals on a clock face. For example in Fig. 2, the position of the tube 56a places its inlet end 58a at the 3 o'clock position with its outlet end 60a disposed at the 12 o'clock position.

Clockwise rotation of the drum assembly 10 will move the inlet end 58a of the tube 56a downwardly from the indicated position in Fig. 2. The first location of interest assumed by the inlet end 58a of the tube 56a is its arrival at the 5 o'clock position. At this time, the open inlet end 58a begins to be submerged below the surface of the body of heat exchange fluid 22 contained in the tank 24 and fluid commences to flow into the tube and rising within the tube to the level of the body of fluid within the tank. The outlet end 60a of the tube 56a, of course, follows the movement of the inlet end of the tube, and, at the time the inlet end 58a has arrived at the 6 o'clock position, the outlet end 60a has moved downwardly to the 3 o'clock position. Since the outlet end 60a is disposed well above the surface of the body of fluid 22 at the time of the greatest submergence of the inlet end of the tube, any steam or vapors trapped within the tube upon the submergence of its inlet end may easily escape through the outlet end of the tube and hence offer no resistance to the free flow of fluid into the tube body.

As the inlet end of the tube is rotated to the 7 o'clock position, the outlet end is lowered to the 4 o'clock position, thus permitting the fluid to flow further into the tube. As the tube is rotated further to move its inlet end to the 8 o'clock position, the outlet end moves to a level below that of the inlet end of the tube, thus trapping whatever fluid remains within the interior of the tube as the tube is rotated upwardly through the body of material M disposed within the drum assembly 10.

It will be noted that the outlet end of each tube is provided with a relatively restricted opening 62, within which is disposed an orifice plug 64. The opening within the orifice plug may be so chosen as to control the rate of flow of fluid from the interior of the tube as the inlet end is elevated above the outlet end. By selecting a suitably sized orifice, the bulk of the fluid may be retained within the tube until the latter has been rotated upwardly to a position clear of the body of material within the drum, such as that assumed by a tube when its inlet end reaches the 12 o'clock position and its outlet end reaches the 9 o'clock position. Conveniently, the orifice plugs 64 are threadedly engaged within the discharge end wall 66 of each tube and by providing sets of orifice plugs having varying diametered openings, the rate of flow of fluid from the tubes may be adjusted, as desired. It should be noted further that as the drum is rotated to return the tube 56a to the position illustrated in Fig. 2, the inlet end is again lowered below the outlet end and hence any fluid which has not drained from the tube is free to flow back to the tank through the open inlet end of the tube.

In cases where the longitudinal length of the central section 12 is not too great, the flow of material through this section may be satisfactorily accomplished merely by the "hydraulic slope" assumed by the material. This is due to the fact that the material piles up to a higher level at the inlet end. Where the length of the central section 12 is somewhat greater, it is often preferable to provide at least one full pitch of an internal screw conveying flight 68 at a desired location in the central section 12. The

radial width of the flight 68 is preferably made such that the tubes 56 may be passed through the flight and thus supported at a location intermediate their ends.

In cases where the unit is to be self-emptying, a narrow conveying spiral 70 may be located throughout the length of the central section 12, terminating adjacent to one of the discharge scoops 72, see Fig. 1.

On the external surface of the annular end plate 20, a plurality of scoops 74 are mounted, one adjacent the inlet end of each tube. The scoops 74 increase the amount of heat exchange fluid fed into the tubes 56. The scoops 74 further provide some additional stiffening to the coupling between the end plate 20 and the discharge section 16.

15 The operation of the structure described below will be set forth in terms of a cooling operation wherein water is employed as the heat exchange fluid. It is believed apparent, however, that heat exchange fluids other than water may be employed and that the structure described 20 above is also adapted to perform a heating operation.

Water, or any suitable heat exchange fluid, may be fed into the tank 24 by means of a valved conduit 76 which is preferably located at the discharge end of the drum assembly. Where a continuous flow of water through the 25 tank 24 is desired, an overflow or outlet opening may be provided at the end of the tank 24 adjacent the feed end of the drum assembly. In cases where the temperatures of the material being handled by the drum are such as to generate steam, the vent for the latter is preferably located 30 adjacent the feed end of the assembly, as indicated at 38.

Material to be cooled is fed into the feed section 14 through the chute or tube 44. Rotation of the drum assembly 10 by the application of a driving force to the driven sprocket or gear 34 rotates the drum in a direction 35 to cause the internal conveying flights 50 to move material from left to right through the feed end section and into the central section 12. In most applications, the "hydraulic slope" assumed by the material within the drum assembly 10 is relied upon to convey the material through the central section 12 of the drum, although if necessary, this conveying action may be assisted by the internal conveying flights 68 and 70. Discharge of material from the drum is accomplished through the discharge section 16 by the internal conveying flight 54.

45 Rotation of the drum assembly 10 sequentially submerges the inlet ends 58 of the respective tubes 56 into the body of water contained within the tank 24. As explained above, each of the tubes 56 receives a charge of water during the passage of its inlet end through the body 50 of fluid and, as the inlet end of the tube is elevated, by the rotation of the drum, above the surface of the fluid, a charge of fluid is retained within the tube. Discharge of the fluid from the respective tubes 56 is controlled by the diameter of the opening within the orifice plug 64 55 located at the outlet end of the tube. The rate of discharge of the fluid through the orifice opening is selected so that a substantial percentage of the fluid charged into the tube during its passage through the tank is retained within the tube until after the tube has been rotated clear 60 of the bed of material within the drum.

Rotation of the series of tubes through the material within the central section 12 of the drum assembly imparts a mixing action to the material to thereby expose a large percentage of the material within the central section 12 to direct contact with the heat transfer surfaces represented by the outer surfaces of the tubes 56. It will be noted that due to the orientation of the tubes 56, the flow of cooling fluid through the tubes is in a direction countercurrent to the direction of movement of material through the drum. Further, since the outlet ends 60 of the various tubes are always located above the surface of the body of fluid while the inlet end of the tube is submerged in the body of fluid, steam or vapor can freely flow from the interior of the tube through the

orifice plug 64 as the tube is being charged with a fresh supply of heat exchange fluid.

While we have described but one embodiment of our invention, it will be apparent to those skilled in the art that the disclosed embodiment is capable of modification. Therefore, the foregoing specification is to be considered exemplary rather than limiting and the true scope of our invention is that described in the following claims.

Having thus described the invention, we claim:

1. A heat exchanger for handling flowable solids comprising a horizontal drum having a feed end and a discharge end, an annular plate flatly mounted on each end of said drum, feeding means communicating with the central opening of the annular end plate at said feed end, discharge means communicating with the central opening of the annular end plate at said discharge end, each of said end plates having an equal number of smaller openings therethrough disposed symmetrically about its central opening, a plurality of tubes mounted on said end plates, each of said tubes extending through a said smaller openings in one of said end plates and through a said smaller opening in the other of said end plates, said last two mentioned openings being angularly displaced relative to each other about the axis of said drum, a tank having a body of heat exchange fluid therein, means supporting said drum for rotation about its axis with said drum partially submerged in said body of fluid to a depth at which said smaller openings are sequentially submerged in said fluid upon rotation of said drum, and means for rotating said drum.

2. A heat exchanger for flowable solids as defined in claim 1 wherein the ends of said tubes at said one of said end plates are angularly displaced by equal amounts in a leading direction with respect to the direction of rotation of said drum from the respective ends of said tubes at the other of said end plates.

3. A heat exchanger for flowable solids as defined in claim 2 including regulating means for controlling the flow of heat exchange fluid from the ends of said tubes at said other of said end plates.

4. A heat exchanger for flowable solids as defined in claim 2 including scoop means mounted on the outer surface of said one of said end plates adjacent each of the smaller openings therein for transferring heat exchange fluid from said tank to said tubes.

5. A heat exchanger for flowable solids as defined in claim 4 including regulating means for controlling the flow of heat exchange fluid from the ends of said tubes at said other of said end plates.

6. A heat exchanger for handling flowable solids comprising a horizontal drum having a feed end and a discharge end, an annular plate having its peripheral edge portion secured to each end of said drum, feeding means communicating with the central opening of the annular end plate at said feed end, discharge means communicating with the central opening of the annular end plate at said discharge end, each of said end plates having an equal number of smaller openings therethrough disposed symmetrically about its central opening at a common radial distance from the axis of said drum, a plurality of tubes mounted on said end plates, each of said tubes extending through a said smaller opening in one of said end plates and through a said smaller opening in the other of said end plates, said last two mentioned smaller openings being angularly displaced relative to each other about the axis of said drum, a tank having a body of heat exchange fluid therein, means supporting said drum for rotation about its axis with said drum partially submerged in said body of fluid to a depth at which said smaller openings are sequentially submerged in said fluid upon rotation of said drum, and means for rotating said drum.

7. A heat exchanger for flowable solids as defined in claim 6 including regulating means for controlling the

flow of heat exchange fluid from the ends of said tubes at said other of said end plates.

8. A heat exchanger for flowable solids as defined in claim 6 including scoop means mounted on the outer surface of said one of said end plates adjacent each of the smaller openings therein for transferring heat exchange fluid from said tank to said tubes.

9. A heat exchanger for flowable solids as defined in claim 8 including regulating means for controlling the rate of flow of fluid from the ends of said tubes at said other of said end plates.

10. A heat exchanger for handling flowable solids comprising a horizontal drum having a feed end and a discharge end, a plate flatly mounted on each end of said

15 drum, each of said end plates having a centrally located materials handling opening therethrough and an equal number of smaller openings disposed symmetrically about the central opening at a common radial distance from the drum, means for feeding flowable solids into said

20 drum through the central opening in said end plate at the feed end of the drum, means for discharging said material through the central opening in said end plate at the discharge end of the drum, a plurality of tubes mounted within said drum and extending between said

25 end plates, each of said tubes extending through a said smaller opening in one of said end plates and through a said smaller opening in the other of said end plates, said last two mentioned smaller openings being angularly displaced relative to each other about the axis of said

30 drum, a tank having a body of heat exchange fluid therein, means supporting said drum for rotation about its axis with said drum submerged in said body of fluid to a depth at which said central openings are disposed above the surface of said body of fluid and said tube openings are sequentially submerged in said body of fluid upon 35 rotation of said drum and means for rotating said drum

11. A heat exchanger for flowable solids as defined in claim 10 including an internal conveying screw flight of at least one pitch mounted within said drum in supporting engagement with said tubes intermediate the ends thereof.

12. A heat exchanger for handling flowable solids comprising a horizontal drum having an enlarged diameter central section, a hollow cylindrical materials feed section of reduced diameter at one end of said central

45 section of reduced diameter at one end of said central section, a hollow cylindrical materials discharge section of reduced diameter at the opposite end of said drum, annular plates at each end of said central section fixedly securing said feed and said discharge sections to said central section in concentric relationship therewith.

50 central section in concentric relationship therewith, a plurality of tubes extending through said central section in symmetric relationship to the axis of said drum, each of said tubes having an inlet end projecting through the end plate at the discharge end of said drum and an outlet end projecting through the end plate at the feed end of

55 end projecting through the end plate at the feed end of said drum at a location angularly displaced about the axis of said drum from its inlet end, a tank having a body of heat exchange fluid therein, means supporting said drum for rotation about its axis with said feed and

60 said discharge sections located above the surface of said body of fluid and said central section partially submerged in said body of fluid to a depth at which the inlet ends of said tubes are sequentially submerged in said body of fluid upon rotation of said drum, and means for rotating said drum about its axis.

13. A heat exchanger for flowable solids as defined in claim 12 including means for regulating the rate of flow of heat exchange fluid from the outlet ends of said tubes.

70 14. A heat exchanger for flowable solids as defined in claim 12 including scoop means mounted on the outer surface of the plate at the discharge end of said drum adjacent each of the inlet ends of said tubes for transferring heat exchange fluid from said tank to said tubes.

75 15. A heat exchanger for flowable solids as defined in

claim 14 including regulating means for controlling the rate of flow of fluid from the discharge ends of said tubes.

16. A heat exchanger for flowable solids as defined in claim 15 wherein the respective ends of said tubes are located at a common radial distance from the axis of said drum, and said inlet ends of said tubes are angu-

larly displaced by equal amounts in a leading direction with respect to the direction of rotation of said drum from the respective outlet ends of said tubes.
